(57) CLAIM

The ornamental design for handle for carrying rolled paper, as shown and described.

DESCRIPTION

FIG. 1 is a perspective view of the handle for carrying rolled papers showing my design carrying a single roll of papers which constitute no part of the design;

FIG. 2 is a perspective view of the handle for carrying rolled papers of FIG. 1 showing my design carrying multiple rolls of paper which constitute no part of the design;

FIG. 3 is a left side view thereof;

FIG. 4 is a right side view thereof;

FIG. 5 is a top view thereof;

FIG. 6 is a bottom view thereof;

FIG. 7 is a front end view thereof; and,

FIG. 8 is a back end view thereof.

The broken line showing of the handle for carrying rolled papers is for illustrative purposes only and forms no part of the claimed design.
